EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER-MOTION FOR LOOMS.

1,327,069.

specification of Letters Patent.

Patented Jan. 6, 1920.

Application filed February 8, 1917. Serial No. 147,468.

To all whom it may concern:

Be it known that I, EDWARD S. STIMPSON, a citizen of the United States, residing at Hopedale, county of Worcester, and State of Massachusetts, have invented an Improvement in Feeler-Motions for Looms, of which the following description, in connection with the accompanying drawings, is a specification, like characters on the drawings representing like parts.

The invention to be hereinafter described relates to feeler looms, and more particularly to the feeler mechanisms of such looms, whereby, when the filling in the active shuttle becomes nearly but not quite exhausted, a train of mechanism is caused to be actuated to effect a change in the condition of the loom.

The change effected in the condition of the loom may cause filling replenishment either by furnishing a fresh supply of filling to the active shuttle or by substituting a shuttle having a working supply therein for the one in which the filling is nearly or substantially exhausted, and while the present invention may be advantageously employed with either of these systems for replenishing the filling, it will be hereinafter described as employed in a loom where the filling is changed in the shuttle.

Feeler mechanisms must be sensitive and responsive to the condition of the filling in the shuttle, otherwise there is liable to be a change of filling at times when a sufficient working supply still remains in the shuttle, in which case there will result undesirable waste; or a change may not be called until the filling is completely exhausted, in which event an objectionable defect is liable to result in the cloth being woven. Either of these conditions is objectionable. An important feature of the present invention, therefore, consists of means which prevents variation in the operation of the feeler and insures uniformity in its detecting action.

In carrying this feature of the invention into practical effect, the feeler or feeler member, which enters the shuttle on each detecting beat to ascertain the condition of the filling, is of the "side swipe" type, and is held from movement longitudinally of the

shuttle on a detecting beat by engagement with the filling so long as a sufficient or working supply is present, but is given such movement when the filling is substantially exhausted to effect replenishment prior to complete exhaustion. In this type of feeler, movement of the feeler member longitudinally of the shuttle when a working or sufficient supply is present on a detecting beat, is prevented by the roughened end of the feeler engaging and, to an extent, sinking into the filling. The feeler is usually held in rearward position or pressed toward the lay by a spring, the effective pressure of which increases as the lay moves to front position on a detecting beat, so that if the feeler is freed to "side swipe" movement as soon as or shortly after it contacts with the filling in the shuttle, the roughened engaging end of the feeler will not be pressed with sufficient energy against the filling to be always held from "side swipe" movement at such time, and a change of filling is liable to result even when a sufficient or working supply is present in the shuttle. Other causes, not necessary to enumerate here, may also bring about premature movement of the feeler longitudinally of the shuttle where the feeler is free for such movement shortly after it engages the filling on a detecting beat.

The above and other important features of the invention will be hereinafter described in connection with the accompanying drawings which show one good practical form or embodiment thereof, and the several features of the invention will then be definitely pointed out by the claims.

In the drawings:—

Figure 1 is a perspective view of sufficient portions of a loom containing the present invention to make clear the construction and operation thereof;

Fig. 2 is a perspective view, parts being omitted, showing the feeler mechanism and relation of parts when the lay is approximately at front position and the shuttle contains a working supply of filling;

Fig. 3 is an enlarged detail in side elevation showing portions of the actuator and operating member;

Fig. 4 is a section on the line 4—4, Fig. 3;

Fig. 5 is a perspective view similar to that of Fig. 2, showing the relation of parts when the lay has moved backward from the 5 position indicated in Fig. 2;

Fig. 6 is a similar view showing the relation of parts when the lay is approximately in front position and the filling is substantially exhausted;

10 Fig. 7 is a detached view showing details of the feeler member and its support; and

Fig. 8 is an underside view of the parts shown by Fig. 7.

The loom frame 1 may be of usual character appropriate to support the operating parts, and is shown as provided with the shipper stand 2 having the usual slot 3 in which the shipper 4 is movable.

15 Mounted in suitable bearings 5 appropriately secured to the loom frame or breast beam at 6, is the change or rock shaft 7, Fig. 1, which may be connected as usual to suitable means for initiating filling replenishment when the shaft is rocked.

20 Adjustably secured to the shaft 7 and rising therefrom is an arm 8 having pivoted thereto at 9 an arm 10, which for identification, will be hereinafter referred to as the actuator, because by frontward movement 25 thereof it actuates or rocks shaft 7 in opposition to its usual spring holding means to initiate filling replenishment.

Secured to the shipper stand or other appropriate supporting means is the feeler stand 11, having a slot 12 through which 30 passes the bolt 13 by which the feeler stand may be adjustably secured in place. The feeler which enters the shuttle on each detecting beat and detects the condition of the 35 filling, is yieldingly mounted on the feeler stand for frontward movement. In the present instance the feeler comprises the rod 14, the front portion of which passes loosely through a bearing 15 sustained by the feeler stand 11, the construction being such that the feeler may be moved frontward and have capacity for swinging movement to a limited extent in a direction longitudinally of the 40 shuttle, as will more fully appear.

45 The feeler 14 has secured thereto a block 16 having side or wing portions 17 which ride upon the feeler stand 11 as it is moved relative to the stand, and a spring normally acts upon the feeler to maintain it in rearward position. In the present instance, the 50 spring is of the coil type 18 which surrounds the feeler, one end of the spring resting against the bearing 15 and its opposite end against the block 16. The filling-engaging 55 end of the feeler 14 is roughened or provided with teeth 19, the construction being such that the roughened or toothed end 19 by engagement with the relative soft filling will prevent movement of the feeler longi-

tudinally of the shuttle in response to its 60 actuating means to be described provided a sufficient or working supply of filling is present as the lay makes its detecting beat.

The block 16 has a portion 20 which extends into a wide slot 21, Fig. 8, formed in 70 the feeler stand, and is provided with an incline 22 adapted to engage a contracted portion or an incline 23 at the rear part of the slot 21, as the feeler moves from a front to the rear under the impulse of the spring 75 18 to thus insure the proper feeling position of the feeler member as the lay goes back. When operating the loom without the shuttle, as is sometimes done, the portion 20 of the block 16 by resting in the contracted 80 portion of the slot 21, prevents lateral or side movement of the feeler.

As hereinbefore noted, the feeler is of the "side swipe" type, that is, it has a movement longitudinally of the shuttle, when, on a 85 detecting beat, there is not sufficient filling in the shuttle to restrain such movement by engagement with the roughened or toothed end 19 of the feeler member. In the illustrated form of the invention, the feeler 90 member 14 passes through a block 24 supported by the feeler stand 11 and guided for sliding movement in a lateral direction or substantially lengthwise of the shuttle by lugs 25 projecting from the feeler stand, 95 Fig. 7. Various modifications of this feature of the invention will suggest themselves, but that described has been found efficient and practical.

The front wall 26 of the shuttle-box is 100 provided with an opening 27, as is also the front wall 28 of the shuttle 29, and through these openings the end of the feeler member 14 passes on each detecting beat to contact with the filling in the shuttle.

Pivotedly mounted at 30 on a suitable stand 31 is a bell crank lever 32, the end 33 of which projects below the actuator 10, and on which the actuator may conveniently rest. The bell crank lever 32 is connected 110 to the feeler member so that lateral or side swipe movement of the feeler member on a detecting beat will cause the actuator 10 to be operatively positioned relative to an operating member to initiate filling replenishment. In the present instance a rod 35 connects the bell crank 32 and slide block 24. This rod may be pivoted to the bell crank at 34 and joined to the slide block 24, by passing the end of the rod through a lug 36 120 extending from the slide block, and to keep the rod and lug in operative relation yet permit them to be readily disconnected, a plate 37 may be secured to the feeler stand and project above or over the extension 36, 125 as indicated in Fig. 1, but various details may suggest themselves as substitutes for connecting the feeler member and bell

crank. The rod 35 may be made adjustable in length, and a convenient form of means to this end is shown as a turnbuckle 38.

The present invention contemplates that means be provided for imparting lateral or side swipe movement to the feeler, when, on a detecting beat, the filling is substantially exhausted. In the present instance, this feature of the invention is accomplished by 10 a spring 39 mounted upon the rod 35, one end of the spring being seated against guide portions 40 of the bracket 31 through which the rod 35 passes and the other end against a collar 41 adjustably secured to the rod, the construction being such that should the filling be substantially exhausted on a detecting beat, the spring 39 will cause the feeler member to be moved laterally or in a direction longitudinally of the shuttle, thereby 15 also placing the actuator 10 in position to be moved forward by its operating member 42, as will more fully appear, to initiate filling replenishment.

Should the feeler member have been 20 moved laterally as and under the conditions described, it is desirable that, it be moved laterally in the opposite direction as the lay goes back in order that the feeler member may assume its proper feeling position, as indicated in Fig. 1. The spring 18 and the inclines 22 and 23, Fig. 8, may under some conditions be quite sufficient to restore the feeler to proper feeling position, but to insure this, the actuator 10 has an inclined 25 or cam portion 43, which, as the actuator 10 is moved forward by its operating member 42 after a call for replenishment by side swipe movement of the feeler member, rides over the end 33 of the bell crank 32, turns it 30 against the tension of the spring 39, and draws the feeler member laterally in an opposite direction so that as the lay retreats, the spring 18 may restore the feeler member 35 to full and proper feeling position.

40 The intermittent engagement of the feeler member with the filling in the shuttle is liable to injuriously affect the yarn. To reduce this injury to a minimum, the feeler member and the spring means for moving or holding it rearwardly should be light and readily responsive to the push of the filling during the beat-up. On the other hand, if the feeler member is free to move laterally or longitudinally of the shuttle at or shortly 45 after engagement with the filling, the pressure of the engaging end of the feeler against the filling, even when a working supply is present on a detecting beat, may not be sufficient to hold the feeler from such lateral movement where the feeler and spring are made so light as not to injure the yarn, and a change of filling will be prematurely made. The present invention, therefore, contemplates that the feeler mem-

ber and the spring for holding or moving it 50 rearwardly, shall be so light that the yarn may not be injured, and the feeler member be locked or held from lateral or side swipe movement until, on the forward movement of the lay, the tension of the spring has 55 been sufficiently increased to cause the engaging end of the feeler to sink far enough into the filling to be effectively held by it from lateral or side swipe movement so long as a working supply of filling is present. 60 More specifically stated, the feeler member is preferably held or locked from lateral or side swipe movement at all times, except when the lay is approximately in front position and the pressure energy of the feeler member against the filling is about the maximum. At this moment the feeler member is freed so that it may move laterally or 65 longitudinally of the shuttle provided the filling is substantially exhausted.

85 The actuator 10 has an end portion provided with shoulders or surfaces 44 and 45, Fig. 3, one each side of a recess 46. The operating member 42 may be any appropriate part moving in the desired timed relation with the lay, and in the present instance, is the cam follower or arm connected thereto. The operating member has a head portion 47 provided with a shoulder or surface 48 adapted to rest upon the surface 44, Figs. 1 90 and 3, when the lay is in rearward position, thereby locking the feeler member from lateral or side swipe movement, so long as the parts 44 and 48 remain in the described relation. On each detecting beat, the lay moves 95 forward and causes the feeler member 14 to enter the shuttle and feel for the filling. As the lay moves farther forward, the feeler member is pushed toward the front of the loom, compressing the spring 18, and 100 causing the roughened end of the feeler member to press with increasing energy against the filling, while the operating member 42 remains at rest. When, however, the 105 forward movement of the lay has increased the spring tension enough to insure that the roughened or toothed end of the feeler member is pressed sufficiently into the filling to hold the feeler member against lateral or side swipe movement provided a 110 working supply of filling is present, the operating member 42 moves on its excursion from the shoulder or surface 44 across the recess 46 to the shoulder or surface 45, and as it passes the recess, it frees the actuator 115 115 and perforce the feeler member. If there be a working supply of filling in the shuttle, Fig. 2, the feeler will have been forced into effective holding engagement with the filling before being freed to lateral or side swipe 120 movement as the head of the operating member passes across the recess 46, and will consequently not move laterally. The head of 125

the operating member will then cross the recess and ride above the surface 45 before the lay, on its backward movement, carries the filling away from the feeler, thereby again locking the feeler member, Fig. 5. If, however the filling be substantially exhausted, as the head of the operating member 42 moves from the surface 44, the spring 39 will force the feeler member laterally, or 10 longitudinally of the shuttle and lift the actuator 10, so that the shouldered portion 48 of the operating member will engage the recess 46 and upon continued frontward movement of the operating member cause 15 the actuator to move frontward, thereby rocking the shaft 7 and initiating filling replenishment, as indicated in Fig. 6. Thus the feeler member is locked from lateral movement at all times, except during the 20 short interval when the head of the operating member is crossing the recess 46, and at such time the action of the feeler member against the filling is such that lateral movement cannot occur unless the filling has been 25 substantially exhausted.

The described feeler motion may be employed in connection with bobbins or filling carriers wound with a bunch. In such cases, the feeler member may act upon the filling 30 or bobbin at one side of the bunch, and, owing to the increased energy with which the feeler member acts before being freed to lateral or side swipe movement, the filling may be exhausted substantially to leave only 35 the bunch upon the bobbin when replenishment is called. In practice, it has been found that there is substantial uniformity in the amount of yarn left on the bobbin as waste by the use of the present invention. 40 This is particularly so where the bobbins are provided with a bunch, but of course, the invention may be advantageously employed in connection with bobbins wound without a bunch.

45 The feeler member is preferably made tubular, thereby rendering it light yet efficient in operation, and in this case the filling-engaging end of the feeler member may be formed by a cap secured to the feeler member, as indicated. Any matter common to this case and the Stimpson Patent No. 50 1,309,226, dated July 8, 1919, is claimed in the patent, and all the claims in this application are directed to subject-matter not disclosed in the patent.

What is claimed is:—

1. In a feeler motion for looms, the combination of a feeler stand having a bearing at its front portion and a slide mounted for 55 lateral movement at its rear portion, a feeler mounted for reciprocating movement in said bearing and slide, and means for moving the slide laterally and swinging the feeler in the front bearing when the filling is exhausted 60 on a detecting beat.

2. In a feeler motion for looms, the combination of a feeler stand having a bearing at its front portion and a slide mounted for lateral movement at its rear portion, a feeler mounted for reciprocating movement in said bearing and slide, a spring normally acting to maintain the feeler in rearward position, and means for moving the slide laterally and swinging the feeler in the front bearing when the filling is exhausted on a detecting 70 beat. 75

3. In a feeler motion for looms, the combination of a feeler stand, a bearing at the front portion of the feeler stand, a slide mounted for lateral movement of and at the 80 rear of the feeler stand, a feeler mounted for reciprocating and swinging movement in the front bearing and for reciprocating movement in the slide, and means for moving the slide laterally on a detecting beat when 85 the filling is substantially exhausted.

4. In a filling replenishing loom, the combination of a feeler, means including a laterally movable spring actuated slide for supporting the feeler in feeling position, a train 90 of mechanism for initiating replenishment of filling when the slide is moved laterally, and connections between the slide and said train of mechanism.

5. In a filling replenishing loom, the combination of a feeler, means including a laterally movable slide for supporting the feeler in feeling position, means for effecting lateral movement of the feeler and slide when the filling is substantially exhausted, a 100 train of mechanism for initiating replenishment of filling when the slide is moved laterally, and connections between the slide and said train of mechanism.

6. In a filling replenishing loom, the combination of a feeler, an actuator, a laterally movable slide through which the feeler extends, connections between the slide and actuator, and means for moving the slide laterally when the filling is substantially exhausted on a detecting beat. 105

7. A feeler motion for looms, comprising, in combination, a feeler member movable in a frontward direction by the filling in the shuttle on a detecting beat and held from 115 movement longitudinally of the shuttle by engagement with the filling until substantial exhaustion thereof, means for moving the feeler member longitudinally of the shuttle about a center intermediate the ends of the 120 feeler member when the filling is substantially exhausted, a laterally movable slide through which the feeler extends, a train 125 of mechanism for controlling the loom operation, and connections between the slide and said train of mechanism.

8. A feeler motion for looms, comprising, in combination, a feeler stand, a feeler member, a spring normally acting to hold the feeler member in rearward position to en- 130

gage the filling on a detecting beat and yielding to permit the feeler member to move frontwardly, means for moving the feeler member longitudinally of the shuttle and 5 prevented from effecting such movement on a detecting beat by engagement of the feeler member with the filling until substantial exhaustion thereof, a laterally movable slide mounted on the rear portion of the feeler 10 stand and through which the feeler extends, an actuator, and connections between the slide and actuator.

9. In a feeler motion for looms, the combination of a feeler stand or support, a 15 feeler member loosely sustained at its front portion for both lengthwise and sidewise movement, a spring normally acting to hold the feeler member in its rear position, means for moving the feeler member sidewise and 20 prevented from effecting such sidewise movement by engagement of the feeler member with the filling until substantial exhaustion thereof, a slide mounted on the feeler stand or support and through which the 25 feeler extends and means for initiating replenishment of filling when the feeler is moved sidewise by its operating means.

10. A feeler motion for looms, comprising a feeler stand or support provided with a 30 bearing at the front thereof, a feeler member having its front portion loosely sustained in said bearing to permit both lengthwise and sidewise movement of the feeler member, means for supporting the rear portion 35 of the feeler member and confining it to sidewise and longitudinal movement independent of the front bearing, means for giving sidewise movement to the feeler member and prevented from effecting such movement by engagement of the feeler member 40 with the filling until substantial exhaustion thereof, and means operative upon sidewise movement of the feeler member for initiating replenishment of filling.

45 11. A feeler motion for looms, comprising, in combination, a feeler stand having a front bearing portion and a rear lateral guideway, a feeler member guided for lateral movement in said guideway and extending 50 into the front bearing portion of the feeler stand, means connected to the guideway to prevent other than longitudinal and sidewise movements of the feeler member, a spring normally tending to hold the feeler

member in rear position, means for moving 55 the feeler member laterally and prevented from effecting such movement by engagement of the feeler member with the filling on a detecting beat until substantial exhaustion of filling, and means operative upon 60 sidewise movement of the feeler member in said lateral guideway for effecting replenishment of filling.

12. In a feeler motion, the combination of a feeler stand having a front bearing portion and a rear laterally movable slide, a feeler passing through the front bearing and rear slide, a train of mechanism to change the operation of the loom, a rod connecting said mechanism and rear slide, and 70 means for moving the feeler and slide laterally when the filling is exhausted on a detecting beat.

13. In a feeler motion, the combination of a feeler stand having a front bearing portion and a rear laterally movable slide, a feeler passing through the front bearing and rear slide, means on the feeler stand for guiding the slide, a train of mechanism to change the operation of the loom, a rod connecting said mechanism and rear slide, and means for moving the feeler and slide laterally when the filling is exhausted on a detecting beat.

14. In a feeler motion, the combination of a feeler stand having a front bearing portion and a rear laterally movable slide, a feeler passing through said bearing and slide, a bridge connected to the feeler between the bearing and slide, means normally 90 tending to hold the feeler in rear position, and means for moving the feeler and slide laterally when the filling is exhausted on a detecting beat.

15. In a feeler motion for looms, the combination of a feeler mounted for reciprocating and swinging movements, a laterally movable slide through which the feeler extends, an actuator, a lever for moving the actuator to operative position, connections 100 between the lever and the laterally movable slide, and means for moving the slide and feeler laterally when filling is substantially exhausted on a detecting beat.

In testimony whereof, I have signed my 105 name to this specification.

EDWARD S. STIMPSON.
